Specification of Letters Patent. Patented Jan. 18, 1916.

Application filed March 15, 1913. Serial No. 754,524.

To all whom it may concern:

Be it known that I, TORRIS H. ALFREDS, a citizen of the United States, and a resident of Chicago, in the county of Cook and State 5 of Illinois, have invented certain new and useful Improvements in Antifriction-Bearings; and I do hereby declare that the following is a full, clear, and exact description thereof, reference being had to the accompanying drawings, and to the letters of reference marked thereon, which form a part 10 of this specification.

This invention relates to improvements in antifriction bearings, more particularly applicable as antifriction side bearings for railway cars and consists of the matters hereinafter described and more particularly pointed out in the appended claims.

In the drawings:—Figure 1 is a view representing a longitudinal central section through my improved side bearing, showing the antifriction elements as they appear when transmitting load. Fig. 2 is a top plan view of the bearing. Fig. 3 is an end 25 view of the same. Figs. 4 and 5 are transverse sections taken in planes indicated, respectively, by the lines 4—4 and 5—5 of Fig. 1. Fig. 6 is a perspective view of the casing with a part broken away to more clearly illustrate the interior construction thereof. Fig. 7 is a perspective view of the cover plate with a wear-plate attached thereto. Fig. 8 is a perspective view of the carriage which supports the antifriction 35 elements. Fig. 9 is a view representing a longitudinal central section through a side bearing embodying my invention in a modified form. Fig. 10 is a transverse sectional view taken in a plane indicated by the line 10—10 of Fig. 9.

Referring now to the embodiment of my invention illustrated in the drawings and particularly in Figs. 1 to 8, inclusive, 10 indicates a casing that is attached to the 45 body bolster 11 of a car and contains and supports the movable parts of the bearing. Said casing is open at its top and bottom and has upright end walls 12, 12, and side walls 13, 13. 14 indicates a cover for the 50 top of the casing which is supported on the side walls of the casing by means of longitudinally extending shoulders 15, 15 thereon, in such manner that the cover may be

dropped into place and seated with its top surface flush with the top of the casing. A 55 wear-plate 16 is secured to the underside of the cover plate 14 by means of rivets 16^a, 16^a. Said wear-plate is of a width equal to the distance between the side walls of the casing and extends the full length of the interior 60 thereof.

The antifriction elements are supported in a carriage 17 suspended within and supported by the casing 10 and capable of a longitudinal movement therein. The carriage, as shown, consists of a rectangular frame (see Fig. 8) having side members 19, 19 and transverse end members 20, 20. Said carriage has end extensions 21, 21, which, as shown, consist of bars, rectangular in 70 cross-section, fixed to its end members 20 in the median plane of the carriage. Said bars extend beyond the end walls 12, 12 of the casing and have sliding bearing in slots 12^a, 12^a, formed in said end walls. Said 75 slots 12^a are open at the top and are extended as indicated at 12^x into the end flanges of the casing (see Fig. 6) so that said carriage with its end extensions, may be inserted into the casing through its open top. 80

The parts of the slots 12^a, 12^a, above the upper edge of the end extensions 21, 21 of the carriage, are closed when the parts are assembled by depending bars 14^a, 14^a, fixed to the ends of the cover-plate 14, and the 85 parts of the slots indicated at 12^x, 12^x, are closed by longitudinally extending lugs 14^b, 14^b at the end of the cover-plate 14. This construction provides a suitable support for the carriage which will permit of no movement thereof, except in a longitudinal direction. 90

The side members 19, 19 of the carriage have bearing grooves or slots 19^a, 19^a, in which are supported the trunnions 23, 23 95 of antifriction elements, in this case rollers 24. The slots 19^a, 19^a are open at the top, so that the rollers 24 may be dropped through the open top of the casing into their proper position in the carriage. 100

Resilient means is provided for returning the carriage with its antifriction elements to a central position in the casing after said antifriction elements in transmitting load have caused the carriage to move 105 from said position toward one or the other

end of the casing and when said elements have ceased to transmit load. Said resilient means in the present instance comprises coiled expansion springs 25, 25 surrounding the extension bars 21, 21 of the carriage and interposed between the end walls 12, 12 of the casing and the transverse end members 20, 20 of the carriage.

The operation of my improved side bearing is as follows: When in the transmission of load from the body bolster to the truck bolster (the truck-bolster being provided with a wear-plate 40) the antifriction elements are rolled toward one end of the 10 casing, they impart movement to the carriage 17 by means of the engagement of their trunnions with the vertical sides of the grooves 19^a in which said trunnions are mounted. As the carriage is moving toward 15 one end of the casing, the supporting members of the carriage will have movement in the slots in the end wall of the casing, compressing the spring at that end of the casing toward which the carriage is moving. 20 When the antifriction elements are released, the expansive action of the spring that has been compressed will return the carriage, and with it the rollers to their initial central position.

30 It may be found preferable to employ a single spring to return the carriage to its normal position and such construction is illustrated in Figs. 9 and 10, wherein like parts are indicated as before. The carriage 30 in this instance comprises side members 31, 31, transverse end members 32, 32, and a central, longitudinally extending, dividing member 33 which divides the carriage into two compartments 30^a, 30^a. The side 35 and central members are provided with bearing slots 19^a in which are supported the trunnions of the antifriction elements. 34, 34 indicate the end extension bars of the carriage, which are adapted for sliding engagement with slots in the end walls of the casing, as before. The end parts 34^a of the 40 said bars are in this case offset upwardly to provide opposing shoulders 37, 37 between which is mounted an expansion coiled 45 spring 39. 38, 38 indicate pins made integral with said shoulders 37 which act to support the ends of said spring. Said 50 spring abuts also at its ends against the end walls of the casing at each side of the slots 55 through which the carriage end bars extend. The side bearing is attached to the bolster by means of bolts 50 the heads of which cooperate with the upper edges of the extension bars 34, to prevent displacement of the 60 carriage in an upward direction when the carriage is moved beyond the position in which the end bars 14^a of the cover-plate prevent such displacement.

The operation of the construction illustrated in Figs. 9 and 10 is quite familiar.

When the carriage in this instance is moved toward one end of the casing, the end of the spring toward which the carriage is moving will remain stationary by reason of its abutment against the end wall of the 70 casing, while the other end of the spring being in engagement with the shoulder 37 of the extension bar of the carriage, will move with the carriage. This places the spring in compression. When the antifriction elements are released, the expansive action of the compressed spring will cause the carriage and its rollers to return to the initial central position.

To introduce the carriage into the casing, 80 the carriage is tilted and one of the supporting members inserted into the slot in the casing with the spring in place. The carriage is then moved toward that end of the casing into which the supporting member 85 has been inserted and the other supporting member is then dropped into the slot in the opposite end wall of the casing. The antifriction elements are placed in position on the carriage, when the cover-plate with 90 its attached wear-plate is dropped in place with the depending lugs thereof engaging the upper edge of the supporting member and thus close the slots in the end walls above the supporting members. The device 95 is thus assembled.

The carriage is supported in the casing by means which allows endwise travel of the same under load but will allow of no tilting of the carriage in a lateral plane, 100 (the supporting members of the carriage being preferably rectangular in cross-section) and thus prevents rattling and undue wear caused by vibration of the car body.

I claim as my invention—

1. In an antifriction bearing, the combination of a casing having apertured end members, an antifriction device including a carriage longitudinally movable in said casing, and extension bars fixed to said carriage 110 in the plane of the movement thereof, said bars extending through the apertures in the casing end members and providing a non-rotative sliding bearing support for the carriage.

2. In an antifriction bearing, the combination of a casing open top and bottom and having side and apertured end walls, an antifriction device including a carriage longitudinally movable in said casing, and extension bars fixed to said carriage in the plane of the movement thereof, said bars extending through the apertures in said casing end walls and providing a non-rotative sliding bearing support for the carriage.

3. In an antifriction bearing, the combination of a casing having side and end walls, said end walls having bearing apertures therein, an antifriction device including a carriage movable in said casing, and

extension bars fixed to said carriage, said extension bars having a non-rotative sliding bearing support in said aperture.

4. In an antifriction bearing, the combination of a casing having side and end walls, said end walls having bearing apertures therein, and an antifriction device including a carriage longitudinally movable in said casing, said carriage being provided at its 10 ends with rigid extension bars, said bars having a non-rotative bearing in said apertures.

5. In an antifriction bearing, the combination of a casing having side and end walls, 15 said end walls having bearing apertures therein, an antifriction device including a carriage longitudinally movable in said casing, extension bars fixed to said carriage, said bars having a non-rotative sliding bearing 20 in the apertures in said end walls and resilient means for centering the carriage in said casing.

6. In an antifriction bearing, the combination of a casing having side and end walls, 25 said end walls having bearing apertures therein, an antifriction device including a carriage longitudinally movable in said casing, extension bars fixed to said carriage, said bars having a non-rotative sliding bearing 30 in the apertures in said end walls and resilient means interposed between the carriage and the end walls of the casing for centering said carriage in said casing, said means comprising springs supported on said 35 bars.

7. In an antifriction bearing, the combination of an open top casing having side walls and slotted end walls, a carriage longitudinally movable in said casing, said carriage 40 having parallel longitudinal side

members and parallel transverse end members, longitudinal extension bars made integral with the end members of the carriage and having sliding bearing in the slotted end wall of the casing, and a cover 45 plate supported by the side walls of the casing adapted to close the opening in the top of said casing, said cover plate having depending lugs which project into and fill that part of the slots in the casing end walls 50 not occupied by the said extension bars.

8. In an antifriction bearing, the combination of a casing open top and bottom, and having side walls and slotted end walls, a carriage longitudinally movable therein, 55 said carriage having parallel side and parallel transverse end members, longitudinal extension bars made integral with the end members of the carriage, said bars being rectangular in cross section and having sliding bearing in the slotted end wall of the casing, a cover plate adapted to close the opening in the top of said casing, said cover plate having depending lugs which project into and fill that part of the slots in the casing 60 end walls not occupied by the said extension bars, and resilient means carried by said bars interposed between the end members of the carriage and the end wall of the casing, said resilient means being adapted 65 for centering the carriage in said casing.

In testimony, that I claim the foregoing as my invention I affix my signature in the presence of two witnesses, this 13th day of March A. D. 1913.
